UNITED STATES PATENT OFFICE

2,063,650

LIME-CEMENT CONTAINER

Graham C. Woodruff, Bronxville, N. Y., assignor
to The L. C. L. Corporation, a corporation of
Delaware

Application November 23, 1931, Serial No. 576,925

2 Claims. (Cl. 294—71)

While I will, for the purposes of illustrating my invention, describe it as being particularly adapted for the shipment of lime and cement in bulk, it will, of course be understood that the use of 5 my improved container is not limited to these particular commodities.

As is well known, cement, prior to my invention, was shipped in bags and each individual bag had to be handled both in loading and unloading on 10 railroad cars and other transportation vehicles, all of which increased the cost of the product. Lime is usually shipped in barrels or in bulk in box cars, requiring considerable handling in loading and unloading, which, likewise, increased 15 the cost of the commodity. In both of these methods of shipment there was no real protection against the elements for the commodity because moisture would penetrate the bags, and in the case of box cars a leak in any portion of the car 20 would affect the lime in that particular zone, and this effect would in many instances be straight throughout the entire area of the box car and result in a loss of the shipment.

The object of my invention is to provide a container, preferably of less than car load lots size, 25 for the shipment of lime and cement in bulk whereby the entire contents of the container could be handled at one operation, and whereby the commodity would be fully protected against the elements. In instances of large buildings, 30 it is possible by my invention to load the container at the point of shipment and ship the container with its load intact to the point of destination and raise the container by a crane, or other 35 means, to the point in the building under construction and deposit the entire contents at the actual point of consumption in the building, thus eliminating a large amount of manual labor.

Another advantage of shipping cement and 40 lime in bulk is that the percentage of loss in shipment is materially reduced.

With these and other objects in view, my 45 invention consists of the parts and combination of parts as will be hereinafter more fully set forth.

In the drawings:

Figure 1 is a side elevation of my improved 50 container.

Figure 2 is a top plan view of the same.

Figure 3 is an end elevation of the container.

Figure 4 is a horizontal section through the 55 container on the line 4—4, Figure 3.

Figure 4A is an enlarged detail sectional view.

Figure 5 is an enlarged detail sectional view of

one of the lower corner portions of the container.

Figure 6 is an enlarged detail sectional view of the door stiffener extensions.

Figure 7 is an enlarged detail vertical longitudinal sectional view through the hatch and hatch door of the container.

Figure 8 is a sectional view on the line 8—8, Figure 5.

Figure 9 is an enlarged detail sectional view.

Figure 10 is an enlarged detail sectional view of the container and door showing the door stiffener extensions.

Figure 11 is an enlarged detail sectional view of the corner construction of the container.

The vertical walls of the container are preferably made from sheet steel, the side walls 12 being provided with vertically extending corrugations 13 which rigidify and strengthen the walls, the lower portion of the sheet being provided with a horizontally disposed corrugation 14. If desired the side walls of the container may be provided with guide shoes 15 which slidably interlock with corresponding guides secured to the side walls of gondola cars whereby the containers are held against shifting on the car, and whereby one or more containers may be removed from the car without impairing the stability of the other compartments on the car.

The end sheets, or walls, 16 are provided with vertically disposed corrugations or rigidifying elements 17 of varying lengths.

As shown in Figure 11 the side and end wall sheets are overlapped at the corners and I connect them by means of an inner post 18 and an outer post 19, all being suitably secured together by means of the rivets 20.

The roof 21 of the container may be of any approved construction and type and is provided with a hatch way 21 (see Figure 7), and on each side of the hatch way I provide a channel or other rigidifying iron 22, the flanges of which project downwardly into the container. This hatch way is further reinforced by angle irons 23 suitably secured. A hatch door 24 having a downwardly extending flange 25 around its perimeter is provided with rigidifying beams 26 to one end of which a hinge member 27 is suitably secured, the other hinge member 27' being secured to the roof 20 and channel beam 22, as shown in Figure 7. It will be noted that the hinge joint and members are spaced rearwardly from the inwardly turned flange 25 of the door. At the free end of the door I provide a locking member 28 adapted to engage the screw thread fastening 55

bolt 29 which is pivotally mounted at 30 on the car roof whereby the door may be securely sealed in position on the container. It will be seen from Figure 2 that I provide the door with two of the 5 beams 26.

The container is provided with lifting links 31 at each corner.

The lower end of the container is provided with a pair of doors 32 each having depending flanges 10 33 around its perimeter, as clearly shown in Figure 5. These doors are provided with reinforcing angle bars 34 secured to a door sheet within the flange 33, each end of the reinforcing bars 34 being provided with an extension 35, which extension extends out under the door flange, as shown in Figure 4A. These doors must fit accurately yet operate freely, proper clearances being provided for that purpose. The door is provided with a hinge member 36 secured to its underface and 15 within the depending flange 33 and materially above the lower edge of the flange 33, which hinge member is secured to another hinge member 37 secured to the side sill 38, the upper end of which member 37 extends within the flange 33 20 of the door to a point near the underface of the door sheet whereby this hinge joint is protected against the elements and leakage.

I secure a sloping lading deflector 39 within the container on all four sides thereof just above the top surface of the drop doors, the deflectors being secured to the side sills 38 of the container base and to the side sheets of the container body, and are preferably mitered at their ends for connection at corners of containers, the connection being preferably welded. These deflectors not 30 only function to deflect the lading toward the door opening, but, as seen in Figure 5, they function as a hood or guard sill, cooperating with the top surface of the door to prevent leakage of the 35 lading, and also prevent entrance of moisture into the container. It will be seen from Figure 5 that the end sills elevate the doors of the container materially above the surface on which the container rests whereby the doors are prevented 40 from coming into contact with any wet surface on which the container may be deposited, thus protecting the lading.

Suitable chains 40 are connected at their lower ends to the extensions 35 of the door stiffeners, 50 said chains being connected at their upper ends to a common plate 40' which, in turn, is connected to the lifting chain 41 having a suitable ring 42 adapted to be engaged by a suitable source of lifting power, said chains 41 passing up through an opening 43 in the roof of the container.

To completely enclose the door operating chains, so as to prevent their contact with the lading, as well as prevent the entrance of moisture into container a U-shaped chain housing 44 60 is suitably secured to each interior face of the end wall of the container, and these housings extend from the underside of the roof sheet down-

ward past the end of each door to the end sill. These housings are clearly seen in Figures 4, 4A and 5. It will be noted from Figure 5 that the lower portion of the chain housings are flared to accommodate spread of the chains 40 to their respective doors. The joint between the top of the chain housing and the roof of the container is closed preferably by welding, or some other approved method of sealing the joint against moisture may be employed. The deflectors 39, as 10 shown in Figure 4A, are extended around the chain housing.

At any chain hole, or opening, 43 and to one side thereof I provide a drop door chain fastener 44, the vertical leg of which is provided with a vertical slot 45 which is wide enough to engage and hold the drop door chain when the doors are in closed position, and I also provide on the roof of the container a support 46 adapted to support the hatch door when in open position. The chain 20 fasteners 44' also function to support the hatch door when it is in open position.

While I have shown and described my preferred construction, it is, of course, understood that changes may be made in the details of construction and arrangement of parts within the scope of the appended claims.

What I claim is:

1. In a drop bottom discharge container side and end sills secured to the bottom of the container and constituting extensions of the walls of the container, a hinge member secured to the end sills with its operative end materially above the lower edge of the end sill, a door having a depending marginal flange and hinged to said hinge member at its underside within the space bounded by the flange, said door being positioned when closed in a plane materially above the lower edge of the end sill, a deflector extending outwardly from the walls of the container over the joint 30 between the flanged edge of the door and container to prevent the loss of lading through said joints, a member secured to the underside of the door and projecting outwardly beyond said flange, and door closing and locking means secured to 35 said member.

2. In a shipping container designed to discharge through its bottom, drop doors secured to the bottom of the container locking means for holding the doors in closed position and permitting them to open, a housing within the container completely housing said means within the container and open at both ends, the lower open end extending below the said doors, whereby moisture in said housing will be discharged 50 through its lower open end outside of the containers, stiffeners extending transversely of said doors having extensions extending beyond the edges of the doors to a point under the lower open ends of said housings, said locking means being 55 secured to said extensions.

GRAHAM C. WOODRUFF.
